UNITED STATES PATENT OFFICE.

ESPIRIDION HIPOLITO, OF LOS ANGELES, CALIFORNIA.

WINDOW-SCREEN.

SPECIFICATION forming part of Letters Patent No. 709,405, dated September 16, 1902.

Application filed February 13, 1899. Serial No. 705,449. (No model.)

To all whom it may concern:

Be it known that I, ESPIRIDION HIPOLITO, residing at Los Angeles, in the county of Los Angeles and State of California, have invented 5 new and useful Improvements in Screened Windows, of which the following is a specification.

An object of my invention is to provide superior means whereby the screen - sash is mounted between the blind-stops of the window-opening without planting any stops on the blind-stop for such purpose; also, to provide superior means for the ready removal and replacing of the screen.

Another object is to provide superior means for adjusting the tension of the springs which hold the sash in place in the window against the force of gravity, so that although the sash will be held by friction where put it can be moved up and down with a minimum expenditure of force.

Another object is to provide superior means for fastening the screen to the sash.

The accompanying drawings illustrate my 25 invention.

Figure 1 is an elevation of a window embodying my invention. Parts are broken away to contract the view and other parts are broken to expose interior construction. Fig. 30 2 is a plan section on irregular line 2 2, Fig. 1. Fig. 3 is an exaggerated plan of a blank for forming the collar-plate for the tongue-adjusting device. Fig. 4 is a section of the same on line 4 4, showing the collar-hole countersunk to admit the adjusting-screw. Fig. 35 5 is an exaggerated view to show the adjusting device in process of manufacture. The collar-plate, the anvil, and the hollow punch for swaging the collar are shown in section. 40 Parts are broken away to contract the view. Fig. 6 is a fragmental detail of the finished adjusting-screw and collar.

A A' indicate the grooved stiles of the sash.

B B' indicate the blind-stops of the window.

a a' indicate the tongue-receiving grooves in the stiles.

b b' indicate the tongue-receiving grooves in the blind-stop.

C indicates a tongue in the groove a'.
c c' indicate transverse slots extending from

one edge of the tongue part way across the tongue.

c" indicates staples set across the mouths of the transverse grooves, respectively. 55

c" indicates pins driven through the stile and through the transverse slots to be engaged by the staples to hold the tongues against removal.

D D' indicate bow-springs in the groove b' 60 and fastened by one end, as by the nails d d', and set, respectively, to press against the staples to force the tongue C outward.

E indicates a tongue in the groove a of the stile A. 65

F indicates a screw swiveled to the stile A and screwed into the stop E, which is made of hard wood, so as to form a nut for the screw. The adjusting-screw F has an annular groove f at its outer end and is preferably 70 provided with a thumb-piece f', by which it can be readily turned.

G indicates a collar-plate which forms a collar extending into the groove f. The collar-plate is fastened to the stile by nails H, 75 driven through the holes g in the collar-plate and into the stile.

The method of manufacturing the adjusting device comprising the screw provided with a collar-plate consists in first perforating a blank of brass or other suitable metal, as at 1, Fig. 3, then countersinking the perforation 2, which is intended for the screw, then placing the same upon an anvil 3, with the screw inserted up through the countersunk hole 2, as shown in Fig. 5, then by means of a hollow punch or swage 4 swaging the countersunk portion 5 of the plate back into position, and thus into the annular groove f of the screw. When the parts 90 are assembled, the hole 2 in the collar-plate is smaller than the body of the screw and is concealed within the annular groove f of the screw.

The screen-netting is fastened in the screen 95 in the following manner: The stiles A A' and rails A" A'" are rabbeted, as at 6, and in the seat of the rabbet at a distance from and between the edges of said seat inwardly-sloping oblique saw-kerfs 7 are cut, and when the 100 frame is assembled the wire-netting 8 is bent into the channels formed by the saw-kerfs,

and strips of molding 9 are laid in the rabbet to extend over and on both sides of the saw-kerf therein and fastened by nails 10 to hold the wire in place on the seat of the rabbet.

- 5 In practice the screen is inserted into the window by first turning the screws F to withdraw the tongue E into its stile, then pressing back the tongue C and inserting it into the groove b' in the blind-stop B'. Then the 10 sash is brought into proper position to make the tongue E register with the groove b. Then the screws F are turned to force the tongue E outward into its groove b in the blind-stop B. Any required pressure for causing friction to sustain the sash can be applied by turning the screws, thus to press the springs D D' firmly against the staples c" to force tongue C outward. By extending the molding-strips on both sides of the groove room is 15 provided for driving the nails 10 into their respective stiles and rails beyond the groove without interfering with the wire-gauze.

Now, having described my invention, what I claim as new, and desire to secure by Letters 20 Patent, is—

1. In a screened window, the combination of grooved stiles; a tongue in the groove of one stile and provided with transverse grooves extending into the tongue from one side; 25 staples set in the tongue and extending over the mouths of the grooves respectively; bow-springs in the stile-groove and respectively fastened at one end, said tongue being seated in the stile-groove with the staples resting 30 upon the bow-springs; nails set through the stile and passing through the slots respectively; a tongue in the groove of the other stile; and means for adjusting the pressure of the tongues.
- 35 2. A screen comprising a frame, the stiles and rails of which are rabbeted and are provided with undercut channels extending along in the seats of the rabbets, respectively, be-

tween the edges of said seats, respectively, and sloping obliquely inward behind said seats; 45 a wire sheet seated upon said seats and having its edges underbent into said channels; molding-strips on the wire sheet in the rabbets and respectively extending on both sides of their respective channels; and nails driven 50 obliquely through the molding-strips into the seats respectively beyond the channels.

3. A screen comprising a frame, the stiles and rails of which are rabbeted and are provided with undercut channels extending along 55 in the seats of the rabbets, respectively, between the edges of said seats, respectively, and sloping obliquely inward behind said seats; a wire sheet seated upon said seats and having its edges underbent into said channels; and molding-strips fastened on the wire 60 in the rabbets and respectively extending on both sides of their respective channels.

4. In a window, the combination of a grooved stile; a tongue moving in the groove 65 in said stile; a collar-plate; and an adjusting-screw through the plate, said screw consisting of a screw-threaded portion and a body portion, the body portion being provided at the end opposite the screw-threaded 70 portion with an annular groove; said collar-plate being fastened to the stile on the edge thereof opposite the groove, and said adjusting-screw being inserted through a hole in the collar-plate and through a hole in the stile 75 and screwed into the tongue and the perforated portion of the collar-plate fitting within the annular groove; the hole in said plate through which said screw is inserted being of less diameter than the body of the screw 80 and being concealed in said annular groove by the walls of said groove.

ESPIRIDION HIPOLITO.
